UNITED STATES PATENT OFFICE.

WALTER O. EILERT, OF VALLEY CENTER, KANSAS.

WRENCH.

1,141,786.

Specification of Letters Patent.

Patented June 1, 1915.

Application filed January 11, 1915. Serial No. 1,626.

To all whom it may concern:

Be it known that I, WALTER O. EILERT, a citizen of the United States, residing at Valley Center, in the county of Sedgwick and State of Kansas, have invented certain new and useful Improvements in Wrenches; and I do hereby declare the following to be a full, clear, and exact description of the invention, such as will enable others skilled in the art to which it appertains to make and use the same.

This invention relates to new and useful improvements in wrenches and has for its principal object to provide a wrench which is particularly adapted for use in gripping pipes or similar cylindrical objects.

Another object of the invention is to provide a wrench which will automatically grip and release the object upon oscillation of the handle.

A further object of the invention is to provide a wrench having a minimum number of parts thus avoiding danger of breakage and also simplifying the construction thereof.

A still further object of the invention is to provide a means for adjusting the jaws of the wrench to pipes or other articles of various sizes.

With these and other object in view the invention consists in the novel combination and arrangement of parts which will be fully set forth in the following specification and accompanying drawing, in which—

Figure 1 is a face view of a wrench constructed in accordance with this invention, Fig. 2 is a longitudinal sectional view showing portions of the jaws broken away to more clearly illustrate the details of construction, Fig. 3 is a transverse sectional view taken on the line 3—3 of Fig. 1, and Fig. 4 is a transverse sectional view taken on the line 4—4 of Fig. 2.

Referring now to the drawing, by characters of reference, the numeral 1 designates as an entirety the handle of the wrench comprising the body 2 having secured thereto the plates 3. These plates may be knurled or otherwise roughened if so desired and extend beyond the end of the body in parallel relation as at 4. The knurled portion of the plates 3 is arranged to form a gripping element which is preferably reduced in size, as clearly shown in the drawing, in order that the user may grab the device firmly. Formed in each of the plates 3 are the arcuate slots 5 which if they were connected

at their ends would form an oval opening. These arcuate slots are to form guides for the jaw pins to cause the jaws to open and close when the device is in operation.

60

The jaws of the wrench comprise the two jaw members 6 and 7, respectively, each comprising the body 8 having formed thereon the arcuate extension 9, the inner face of which is provided with a plurality of transverse ribs 10 to form a gripping portion for pipes and the like. Adjacently formed with relation to the portion 10 are the slot faces 11 which extend from the outer terminal of the arcuate faces to the end of the jaw. Suitable tapered extensions 12 are formed on the bodies 8 at the ends opposite the arcuate extensions 9 and these tapered extensions are provided adjacent their free terminals with suitable recesses 13, the use of which will appear hereinafter. The body 8 of the jaw member 6 is reset as at 14 to receive the tongues 15 which are screwed or otherwise secured as at 16 to the body 8 of the jaw member 7. These recessed portions 14 and the tongues 15 are designed to form guides to hold the jaw members 6 and 7 in proper position and it will thus be seen that the jaw members will be slidable with relation to each other, yet held in direct alignment. Each of the bodies 8 is provided with a suitable aperture 17 through which the pin 18 extends. These pins 18 extend beyond the faces of the jaw members and into the arcuate slots 5 to form a means whereby the jaws are held in place in the handle.

80

Pivots secured as at 19 in each of the recesses 13 is a suitable threaded stem 20 and the threads on the opposite stems are respectively left and right and are arranged to receive the turn buckle 21 in order that the distance between the jaws may be adjusted.

90

While the arcuate slots 5 are designed to open and close the jaws upon oscillation of the handle with relation thereto, I also provide a suitable V-shaped leaf spring designated generally by the numeral 22 to assist in opening the jaws and this spring comprises the arms 23 and bite portion 24 which is bent to cause the arms to diverge toward their free terminal. The end 25 of one of the arms is arranged to extend into a suitable notch 26 formed in one of the bodies 8 which is designed to retain the spring in place to prevent its accidental removal.

100

105

110

It will be apparent from the foregoing that in use, the jaws are first adjusted by the adjusting of the turn buckle 21 on the threaded stems 20 and the wrench is then seated on the article which is to be turned. Upon oscillating the handle with relation to the jaws it will be apparent that the jaws will close and firmly grip the article thus enabling the user to turn the same. When 10 it is desired to change the position of the grip of the wrench on the article which is being turned the handle is straightened with relation to the jaws and it will be apparent that the said jaws will return to their initial 15 position at which time the user again turns the handle and thus causes the article which is being operated upon to rotate in one direction only. Should it be desired to reverse the direction of the rotation the handle is 20 oscillated with relation to the jaws in the opposite direction, thus causing the article to be gripped and enabling the user to turn the same oppositely.

While in the foregoing there is shown and 25 described the preferred embodiment of this invention, it is to be understood that such changes in combination and arrangement of parts may be made as may fall within the scope of the claims.

30 What is claimed is:—

1. A wrench of the character described including a handle having parallel extensions, said parallel extensions being pro-

vided with arcuate slots near one end, jaw members, pins extending through the jaw members and into the arcuate slots to hold the jaw members in place, guides carried by one of the jaw members and jaw faces formed at the ends of the jaw members, the arcuate slots being so shaped as to cause the 40 jaw members to close upon movement of the handle in relation thereto.

2. A wrench of the character described including a handle, parallel extensions formed on the handle, said parallel extensions being 45 provided with arcuate slots, said slots being so positioned that if they were joined they would form an oval extending transversely of the handle, jaw members between the parallel extensions in the handle, pins extending through the jaw members and into the arcuate slots to engage the walls thereof and cause the jaw members to close, guides carried by one of the jaw members to hold the two jaw members in direct alinement, means 50 carried by the inner ends of the jaw members to adjust the distance between the outer ends thereof and a spring to force the outer ends of the jaw members apart.

55 In testimony whereof W. O. EILERT affixes his signature in presence of two witnesses.

WALTER O. EILERT.
